[57] CLAIM

The ornamental design for a fishing lure, as shown and described.

DESCRIPTION

FIG. 1 is a perspective view of a fishing lure incorporating our new and ornamental design;
FIG. 2 is a side elevation view of the fishing lure shown in FIG. 1;

FIG. 3 is a side elevation view showing the opposite side of the fishing lure from that shown in FIG. 2;
FIG. 4 is a top plan view of the fishing lure;
FIG. 5 is a bottom plan view of the fishing lure;
FIG. 6 is a front elevation view of the fishing lure; and,
FIG. 7 is a rear elevation view of the fishing lure.

FIG. 1.

FIG. 2.
